H. C. BERKEY,
ELECTRIC MINING APPARATUS.
APPLICATION FILED JUNE 18, 1921.

1,407,119.

Patented Feb. 21, 1922.

UNITED STATES PATENT OFFICE.

HARVEY C. BERKEY, OF CLAREMONT, NEW HAMPSHIRE, ASSIGNOR TO SULLIVAN MACHINERY COMPANY, A CORPORATION OF MASSACHUSETTS.

ELECTRIC MINING APPARATUS.

1,407,119.

Specification of Letters Patent. Patented Feb. 21, 1922.

Application filed June 18, 1921. Serial No. 478,506.

To all whom it may concern:

Be it known that I, HARVEY C. BERKEY, a citizen of the United States, residing at Claremont, in the county of Sullivan and State of New Hampshire, have invented certain new and useful Improvements in Electric Mining Apparatus, of which the following is a full, clear, and exact specification.

10 My invention relates to electric mining apparatus.

It has for its object to provide an improved means for protecting the operator of an electric mining machine or kerf cutter from shocks encountered when through grounding or the like, the machine frame is charged. Another object of my invention is to provide improved means whereby the mining machine is grounded at a point removed 20 from the operator in such a manner as to enhance the safety of the latter. These and other objects and advantages of my improved construction will hereinafter more fully appear.

25 In the accompanying drawings one embodiment of my invention illustrating the same as applied to a mining machine of the room and pillar type has been shown for purposes of illustration, the drawings showing diagrammatically a mining machine in a room or the like with its truck remaining upon the mine track and the machine removed from the truck and upon the mine bottom.

35 In this illustrative construction I have shown a mechanism of standard construction including a machine 1 and a transport truck 2 therefor adapted to be propelled thereby in a usual manner, the machine 40 herein being of the direct current type and having thereon a usual motor including an armature 3 and field windings 4 with a resistance controller 5 connected in the circuit. As shown, the motor is supplied with 45 current through conductors 6 and 7 united into a cable 8 which in turn again branches at its rear end into the component conductors 6 and 7 which are in turn connected through suitable connector plugs to a suitable cable reel 9 mounted on a part trans-

50 portable with the truck, herein on the rear end of the truck, and connected to conductors 10 and 11 of which the conductor 10 is connected to the main trolley wire 12 in the 55 entry through a suitable clip 13 while the

conductor 11 is connected to one of the usual metallic main line mine rails 14 by a ground clip 15.

In the use of such a standard construction when, through grounding or the like, 60 current is transmitted to the frame of the mining machine 1, the current may, if the operator handling the controls is standing in a wet spot, pass from the machine frame through his body to ground, resulting in 65 serious injuries to the operator. The same result may occur when the machine happens to be resting upon wood or the like and the operator is standing upon the bottom. To meet this situation, I have provided a supplemental conductor 16 attached at its forward end to the machine frame and extending rearward through the cable 8 to the truck, to the metallic frame of which its rear end is connected at 17. Thus, it will 70 be noted that the machine frame is always connected through the conductor 16 to ground through the truck wheels and the room track rails in such a manner that irrespective of contact of the operator with the 75 machine, all danger of injury to the operator is prevented.

While I have in this application specifically described one embodiment which my invention may assume in practice, it will be 80 understood that this form of the same has been chosen for purposes of illustration and that the invention may be modified and embodied in various other forms without departing from its spirit or the scope of the 85 appended claims.

What I claim as new and desire to secure by Letters Patent is:—

1. In a mining apparatus, an electric mining machine disposable on the mine bottom, 90 means for supplying current flow therethrough and to ground at a distant point from said machine when the latter is on the bottom, and supplemental means connected to the machine frame and to ground at a distant point for removing a charge from said frame.

2. In a mining apparatus, an electric mining machine disposable on the mine bottom, 95 means for supplying current flow through said machine when on the bottom including a reel supported on a trackway and supply and ground return conductors extending through said reel, and supplemental charge removing means connected to the machine 100

110

- frame and to ground at a distant point from said machine.
3. In a mining apparatus, a mining machine disposable on a mine bottom, means for supplying current flow therethrough when on the bottom comprising a reel supported on a trackway and a cable comprising supply and ground return conductors extending between said machine and said reel, and supplemental means operative to remove a charge from the machine frame and included in said cable.
4. In a mining apparatus, an electric mining machine disposable on the mine bottom, a transport truck therefor, current supply means for said machine including a reel transportable with said truck and a cable comprising supply and ground return conductors extending between said machine and said reel, and supplemental means included in said cable for removing a charge from the machine frame when the latter is on the bottom.
5. In a mining apparatus, a trackway, a transport truck, an electric kerf cutter transported on said truck and disposable on the mine bottom, a reel transportable with said truck, current supply and ground return means for said cutter comprising supply and ground return conductors extending through said reel, and supplemental means connected to the cutter frame for removing a charge from said frame when the latter is on the
- bottom and grounding said frame on said trackway.
6. In a mining apparatus, a trackway extending along an entry and into a room, a transport truck, an electric kerf cutter transported over said trackway on said truck and disposable on the mine bottom, a reel transportable with said truck, current flow supply means connected to a source of current supply in the main entry and extending through said reel and said kerf cutter when the latter is on the bottom and back through said reel to a ground return on said trackway in the main entry, and means for grounding the kerf cutter frame on the trackway when said frame is disposed on the mine bottom in a room.
7. In a mining apparatus, a trackway, a transport truck, an electric kerf cutter transported thereon over said trackway and disposable on the mine bottom, a reel transportable with said truck, current flow supply and ground return means between said reel and said kerf cutter when the latter is on the bottom including conductors extending through said reel, and a supplemental ground connection between the kerf cutter frame and a part of said truck operative when said cutter is on the bottom to remove a charge from its frame.

In testimony whereof I affix my signature.

HARVEY C. BERKEY.
